By Attorney
C. Dickinson

UNITED STATES PATENT OFFICE.

JOHN A. AKSDAL, OF SEATTLE, WASHINGTON.

SHINGLE-GAGE.

1,256,192.

Specification of Letters Patent. Patented Feb. 12, 1918.

Application filed May 29, 1917. Serial No. 171,767.

To all whom it may concern:

Be it known that I, JOHN A. AKSDAL, citizen of the United States, residing at Seattle, in the county of King and State of Washington, have invented a certain new and useful Improvement in Shingle-Gages, of which the following is a specification.

My invention relates to improvements in shingle gages of that class employed by shinglers in the operation of shingling a house, and the object of my invention is to provide an extensible shingle gage which shall be adapted to facilitate the operation of gaging the distance between the horizontal line extending along the lower edge of a row of shingles already nailed to the side or roof of a house, and the horizontal line along which is to extend the lower edge of the next upper row of shingles to be nailed to said side or roof of said house, and which gage shall be further adapted to support the shingles of said next upper row in exact alinement with each other until they are all nailed to fasten them in their relative positions.

Another object of my invention is to provide a shingle gage that shall embody a plurality of separable like sections, any one of which may be separately used when short rows of shingles are to be nailed to a house; and two or more of which may be united for conjoint use when longer rows of shingles are to be so nailed.

I accomplish these objects by devices illustrated in the accompanying drawings, wherein—

Figure 1 is a view in front elevation of a shingle gage embodying my invention;

Fig. 2 is a fragmentary view of the same in horizontal section on broken line 2, 2 of Fig. 1;

Fig. 3 is a view of the same in vertical section on broken line 3, 3 of Fig. 1, showing it in its operative position when used to shingle the vertical side of a house; and

Fig. 4 is a view of parts of the same in vertical section on broken line 4, 4 of Fig. 1, showing said parts in their operative positions when used to shingle an inclined roof of a house.

Referring to the drawings, throughout which like reference numerals indicate like parts, 5 designates one section of a gage-bar having an integral flange 6 that projects at a right angle from one side of one of its edge portions throughout the length thereof,

which flange 6 serves as a straight-edge and which also tends to make the gage-bar inflexible.

One end portion of the section 5 of said gage-bar is provided with a tongue 7 that is rigidly fastened to the flanged side thereof to extend therebeyond with its inner side surface in the same plane with said flanged side of the section 5 of said gage-bar, said tongue 7 being provided with integral lugs 8 which project in opposite directions from the side edges of its outwardly projecting end portion, and being further provided with a hole 9 as shown in Fig. 1. 70

The other end portion of the section 5 of the gage-bar is provided with two spaced cleats 10 and 11 disposed parallel with each other, one adjacent to the inner side of the flange 6 and the other adjacent to the opposite edge of said section 5, the inner end portions of said cleats 10 and 11 being offset to form spaces within which are removably disposed lugs 12, like the lugs 8 of a tongue 13 which is like the tongue 7 of another 80 abutting section 14, said tongue 13 being clamped in its position against the adjacent end portion of the section 5 by a clamping screw 15 and wing nut 16 thus separably to unite the two sections 5 and 14 to form a 85 straight unitary gage-bar, as more clearly shown in Fig. 2.

Releasably clamped to the flanged side of each of the sections, as to the section 5, by means of clamping screws 17 and 18 and 90 wing nuts 19 and 20, respectively, are two angular brackets 21 and 22, respectively, as shown in Figs. 1 and 3, one portion of each of which brackets 21 and 22 projects over the outer edge surface of the flange 6 to extend 95 for a distance therefrom in the same plane thereof.

Rigidly fastened to both of the outer end portions of the brackets 21 and 22, is a bar 23 of a length equal to the length of the section 5, and which bar 23 is disposed to extend parallel with the section 5 with its end surfaces registering with the respective end surfaces of said section 5, as shown in Fig. 1. 100

Releasably clamped to the flanged side of 105 each of the sections, as to the section 5, by means of clamping screws 24 and 25 and wing nuts 26 and 27 respectively, are two brackets 28 and 29, respectively, integral with each of which brackets 28 and 29 is a 110 downwardly projecting member of an extensible gage-rod (as members 30 and 31 re-

spectively) to the lower end of which is screwed another member, (as members 32 and 33 respectively) thus to extend the length of said gage-rod, and each of said 5 gage-rods is provided with a scale of division marks indicating inches and fractions of inches, as shown in Fig. 1.

Mounted on each of the gage-rods, to be 10 slidably movable to different positions thereon, is a gage-block (as gage-blocks 34 and 35) which is provided with a set screw (as set screws 36 and 37) which may serve to 15 secure its associated gage-block at a desired position on the gage-rod in an obvious manner.

Each of the gage-blocks 34 and 35 is provided with an integral prong (as prongs 38 and 39 respectively) which is of the form of a thin wedge and which is disposed to extend 20 toward section 5 in a line parallel with and spaced from the gage-rod with which it is associated as more clearly shown in Figs. 3 and 4.

The operation of a gage embodying my 25 invention in the manner described is as follows:

When the vertical side of a house is to be shingled all parts of the gage are assembled as shown in Fig. 1 whereupon the prongs 38 and 39 are forcibly disposed to project upwardly between the wall 40 of a house and the bottom end portion of a shingle (as the shingle 41 shown in Fig. 3) of the row of shingles last nailed to the wall 40 in which 30 positions said prongs will be maintained by pointed screws, as screws 42 and 43 which are adjustably disposed to extend through sidewise projecting portions of the gage-blocks 34 and 35 respectively, to force their 35 pointed ends into shingles of the next lower row, as into the single 44 of Fig. 3.

When the prongs 38 and 39 are thus secured in their positions, the gage-rods are 40 adjustably moved in the gage-blocks 34 and 35 to positions, indicated by division marks 45 of the scale on the gage-rods, that will accurately dispose the upper edge surface of the section 5 in a horizontal plane that is at a required distance above the bottom edge of 50 the row of shingles represented by the shingle 41 in Fig. 3.

With the section 5 in such horizontal position, shingles of the next row to be nailed, like the shingle 45 in Fig. 3, are disposed 55 side by side with their bottom ends resting on the upper surface of the flanged edge of said section 5, in which position they are fastened by nails to the wall 40, the adjacent bar 23 serving to prevent the shingles from 60 displacement by swinging away from the wall 40 before they are fastened to the wall 40 by nails.

After the row of shingles has been nailed 65 to the wall 40 then the screws 42 and 43 are unscrewed, till their points are disengaged

from the adjacent shingle, and the prongs 38 and 39 are withdrawn and inserted under shingles of the row that has just been nailed and the operation is then repeated in an obvious manner.

Thus, all rows of shingles may be nailed 70 to the vertical side of a house in exact parallel lines with the bottom edges of adjacent ones of said rows separated by a desired distance.

If it be required to shingle an inclined roof of a house, then the bar 23 becomes unnecessary since shingles disposed with their bottom ends in engagement with the flanged edge of section 5, as shown in Fig. 4, can have no tendency to move from their positions, and said bar 23 is removed by unscrewing the winged nuts 17 and 18 from the clamping screws 19 and 20 and removing the brackets 21 and 22 to which said bar 23 80 is fastened.

Manifestly, sections, like section 5, may be of the same or of different lengths and any number of them may be connected together to form a unitary structure of a desired length as conditions may require.

Obviously, changes may be made in the forms, dimensions and arrangement of parts of my invention without departing from the spirit thereof.

What I claim is:

1. A shingle gage of the class described, which embodies a plurality of sections separately joined end to end, each section comprising a straight bar provided with a flange 100 projecting from one side of one of its side edge portions; a plurality of extensible gage-rods attached to each section to project outwardly from the other one of its side edge portions in a plane parallel with and spaced from the planes of the unflanged side of said section, said gage-rods being provided with division marks of a scale representing units of distance; a gage-block slidably mounted on each of said gage-rods, each of said gage-blocks being provided with an integral wedge-like prong adapted to be forcibly inserted between a wall and the lower edge portion of a shingle nailed to a house that is to be shingled; and releasable 110 means for fastening said prong in its operative position between said wall and said shingle.

2. A shingle gage of the class described which embodies a plurality of sections separately joined end to end, each section comprising a straight bar provided with a flange 120 projecting from one side of one of its side edge portions; a plurality of extensible gage-rods attached to each section to project outwardly from the other one of its side edge portions in a plane parallel with and spaced from the planes of the unflanged side of said section, said gage-rods being provided with division marks of a scale repre- 125

senting units of distance; a gage-block slid-
ably mounted on each of said gage-rods,
each of said gage-blocks being provided with
an integral wedge-like prong adapted to be
5 forcibly inserted between a wall and the
lower edge portion of a shingle nailed to a
house that is to be shingled; releasable
means for fastening said prong in its oper-
ative position between said wall and said
10 shingle; two removable brackets attached to
each of said sections, each of said brackets
being provided with an integral portion that
projects over the flange of said section in a
plane parallel with and spaced from the un-
flanged side of said section; and a bar se- 15
cured to both of the outer ends of said two
brackets to extend in a position parallel with
and spaced from said section.

In witness whereof, I hereunto subscribe
my name this 19th day of May, A. D., 1917. 20

JOHN A. AKSDAL.
